CLAIM

The ornamental design for an eyeglass display stand unit, as shown and described.

DESCRIPTION

FIG. 1 is a top, front, right side, perspective view of an eyeglass display stand unit of the invention;

FIG. 2 is an enlarged front elevational view thereof;

FIG. 3 is a top plan view of FIG. 2;

FIG. 4 is a left side elevational view of FIG. 2, the right side being a mirror image thereof;

FIG. 5 is a back elevational view of FIG. 2; and,

FIG. 6 is a bottom plan view of FIG. 2.
